UNITED STATES PATENT OFFICE.

AURELIUS SMITH, OF INDIANAPOLIS, INDIANA.

REVERSIBLE CUSHION SHOE HEEL.

Application filed May 19, 1922. Serial No. 562,230.

To all whom it may concern:

Be it known that I, AURELIUS SMITH, a citizen of the United States, residing at Indianapolis, in the county of Marion and 5 State of Indiana, have invented a new and useful Reversible Cushion Shoe Heel, of which the following is a specification, reference being had to the accompanying drawings.

10 This invention relates to the heels of shoes or boots of the type adapted to be worn by human beings, the invention having reference more particularly to reversible heels, and especially of the cushion type 15 for shoes or boots.

An object of the invention is to provide an improved reversible heel structure which shall be capable of being varied both as to dimensions and contour to suit dealers 20 therein who may cater to the wants of customers.

Another object is to provide a shoe heel which shall have reversible wearing parts which may be readily removed and changed 25 so as to bring unworn portions of the heel into the place of portions which may have been worn away in use, to the end that the wearing part of the heel shall be renewable and therefore long-lived and economical.

30 A further object is to provide a reversible shoe heel which shall have an expandable or contractible casing part in which body parts of different dimensions may be held and which permits the said body part to be reversed and also inverted when desired, 35 which casing part may be cheaply constructed and not be liable to be fractured in use while being of light weight.

With the above-mentioned and other objects in view, the invention consists in a composite heel of improved construction for shoes or the like, and having a flexible casing part and a changeable body portion which preferably is elastic; and, the invention 45 consists further in the parts and combinations and arrangements of parts as hereinafter particularly described and further set forth in the appended claims.

50 Referring to the drawings, Figure 1 is a fragmentary perspective view of a shoe or boot provided with the improved heel as preferably constructed; Fig. 2 is a front plan or bottom of the casing part of the heel as preferably constructed; Fig. 3 is a view of the forward portion of the casing part, partially in section; Fig. 4 is a lon-

gitudinal central sectional elevation of the improved heel and adjacent portions of the shoe; Fig. 5 is a plan of the elastic body part of the improved heel partially in section; Fig. 6 is a perspective view of the filling-block with which the casing part preferably is provided to change the normal external contour thereof; Fig. 7 is a plan of the casing part blank ready to be shaped to the required contour.

In the different figures of the drawings similar reference characters indicate corresponding or like elements or features of construction herein referred to in detail.

In the drawings the numeral 1 indicates the rearward or heel portion of the upper part of a shoe having a sole which as shown comprises two parts 2 and 3 and an inner sole 4.

The casing part of the heel preferably is composed of stamped sheet metal in order that it may be bent to conform to such contour as may be desired. The casing part comprises an inclosing-wall that is approximately or may be oval in plan but preferably comprises a curved rear portion 5 to which straight sides 6 and 7 are connected, and curved forward portions 8 and 9 extending from the side wall portions and 80 connected in overlapping adjustable arrangement to permit variation in width of the casing part which, being flexible, may be slightly varied so as to conform to shoe soles of various dimensions. The curved forward portions have apertures 10 and 11 adjacent to the ends thereof, at least one of which is elongated as a slot, a bolt 12 being placed in the apertures and provided 85 with a nut 13 whereby the forward casing portions are adjustably secured together. The rearward portion 5 has an ear or foot 14 on its inner side adjacent to the rear or base end thereof, the side wall portions have similar ears 15 and 16, and the forward wall portion has likewise an ear 17 90 on one of the parts thereof, each ear having an aperture 18 therein. The casing part is arranged with its back or base end against the shoe sole in proper position 95 and secured to the sole by means of screws 19 placed in the apertures in the ears and screwed into the shoe sole.

When an approximately oval heel is not desired the straight sides 6 and 7 are made sufficiently long to correspond externally to the shape of heel commonly used, and to

avoid the cost of bending specially shaping the metal of the casing wall two corner blocks 20 and 21 preferably are provided, each of which has a concavely curved inner 5 side 22 corresponding to the curvature of the forward portions 8 and 9, the outer side of each block having relatively right angled faces so as to form corners on the forward casing portions to which the 10 blocks are secured, so that the side faces of the blocks shall form continuations of the outer sides of the portions 6 and 7 respectively, each block having a screw-threaded socket 23 receiving a screw 24, the 15 wall portion of the casing having apertures 25 and 26 through which the screws extend respectively.

The body part or portion of the heel is composed of suitable material, being preferably 20 rubber composition so as to be elastic, and comprises a part 27 of suitable thickness and plan, dimensions corresponding to the casing part, as shown the body part having a curved rear end 28, straight side portions 25 and 30 and a curved opposite forward end 31. Preferably one or more similar body parts 27' are combined in one heel to obtain the maximum wearing surface. One side of each body part has a central recess 32 30 therein and the opposite side has a similar recess 33 therein, and the part has also a central aperture 34 connected with the bottoms of the recesses. The body portion, composed of one or more parts as above indicated, is arranged in the casing part and covers the securing devices thereof, and being of proper thickness it extends beyond the casing part front, a washer 35 is arranged in the forward recess 33, and a 40 wood-screw 36 is inserted through the apertures 34 and screwed into the shoe sole, the head of the wood-screw being seated in the washer.

Each elastic body part of the heel preferably 45 has a layer of fabric reinforcement 37 therein that is imbedded in the rubber composition, any suitable number of layers desired being used.

The casing part is cheaply composed of 50 a stamped oblong plate 38 having on one edge a plurality of extensions 39, 40, 41, and 42 having each an aperture 18 therein, and the apertures 10 and 11 and 25 and 26 are punched in the plate, the projections 55 being subsequently bent over at right angles to the plate to constitute the securing-ears.

In practical use the body portion of the heel deadens sound when composed of non-metallic substance such as wood or vulcanized fibre, and when composed of rubber 60 composition it yields and operates as a cushion when the weight of the wearer is placed upon it, the central portion having the recesses therein possessing the greater 65 degree of elasticity to absorb the shocks

ordinarily transmitted to the wearer as his weight comes fully and squarely upon the heel, while the more dense or less yielding portion adjacent to the edge of the body portion withstands thrusts as the rear edge 70 of the heel is placed in inclined position upon the ground in the act of walking. As the rearward portion becomes worn away in use as commonly occurs the heel becomes 75 uncomfortable to the wearer and also unsightly; but the central screw 36 may be readily removed, permitting the body portion of the heel or the outer part thereof to be removed and reversed so as to bring the 80 unworn forward portion to the place previously occupied by the worn portion, after which the screw may be again inserted in place. After the forward and rearward portions of one side of an elastic part have become worn away objectionably the part 85 may be inverted or turned over so as to bring the unused side to the front. When the heel contains several body parts or layers, the inner layers may be in turn transferred to the front or normal lower position, the objectionably worn parts or layers being 90 shifted to or towards the shoe sole with resulting long life of the heel. When all the body parts have become so worn at the edges 95 as to be useless they may be readily replaced by new parts which may be kept in stock for repair purposes.

Having thus described the invention, what is claimed as new is,—

1. A reversible shoe heel including a casing part having opposite forward and rearward wall portions that have curved inner sides, the forward wall portion having two 100 projections spaced apart on the outer side thereof, the projections having approximately plane outer faces.

2. A reversible shoe heel including a casing part having curved opposite forward and rearward wall portions, the forward wall portion having two corner blocks spaced apart on the outer side thereof, the blocks having approximately plane outer faces, and a body part reversibly secured in and filling the casing part and projecting beyond the normally lower end thereof.

3. A reversible shoe heel including a casing part having opposite forward and rearward wall portions that have curved inner sides, the forward wall portion having two projections spaced apart on the outer side thereof, each of the projections having approximately plane relatively right-angled outer faces, and a body part having opposite curved ends and reversibly secured in and filling the casing part.

4. A reversible cushion shoe heel comprising a flexible casing part having two opposite straight side wall portions and two oppositely curved forward and rearward wall portions, each of said portions having 130

an ear on the inner side thereof to receive a securing screw, the forward wall portion being composed of two overlapping and relatively adjustable slotted parts and provided 5 with a clamp bolt securing the parts together, the forward wall portion having two corner filling blocks spaced apart and secured to the outer side thereof, the blocks having approximately plane outer faces extending forward from the outer faces of 10 said straight wall portions, and an elastic

body part embraced in the casing part and projecting beyond the front end thereof, the body part covering said ears and having an aperture central therein to receive a securing screw and a recess to receive the head of the screw. 15

In witness whereof, I have hereunto set my hand at Indianapolis, Indiana, this 18th day of May, A. D. one thousand nine hundred and twenty-two. 20

AURELIUS SMITH.
